UNITED STATES PATENT OFFICE.

JOHN DIX MORGAN, OF NEW YORK, N. Y.

PRODUCTION OF CYANOGEN COMPOUNDS.

1,278,493.

Specification of Letters Patent. Patented Sept. 10, 1918.

No Drawing.

Application filed June 30, 1917. Serial No. 177,863.

To all whom it may concern:

Be it known that I, JOHN DIX MORGAN, a citizen of the United States, and a resident of New York city, in the county of New York and State of New York, have invented certain new and useful Processes for the Production of Cyanogen Compounds, of which the following is a specification.

My invention relates to that class in which 10 a cyanogen compound is produced through the combination of an initially combined metal of the alkaline group, with carbon and with nitrogen, which may be initially free, or admixed with other gases and in 15 which the solid materials employed are first finely comminuted and then mixed together with or without a catalytic material, suitable for lowering the temperature for the combination of the active elements, and 20 is directed among other things, toward providing such an extended surface of the component materials for instant contact with the nitrogen as to reduce the time required for the completion of the chemical reactions 25 involved, to an inconsiderable period, and to the intermittent removal of the treated material from the reducing chamber while in a plastic condition and without substantial interruption of the continuity of the 30 process.

An examination of the art shows that in the production of cyanogen compounds by combining free nitrogen with an initially combined alkali metal and carbon, iron was 35 used as a catalytic agent to reduce the temperature at which the reaction occurred, as far back as in 1839, when a mixture of coke, cinder or coals, potassium carbonate, (potash or pearl ash) and iron turnings ground 40 to a coarse powder were employed by Lewis Thompson for the production of potassium cyanid by heating the mixture in the presence of atmospheric air, (English periodical, *The Mechanics Magazine* No. 822 p. 92). 45 Here by the powdering of the iron an extended catalytic surface was obtained.

The proportions in which the solid materials were used have since been only slightly varied.

50 This (Thompson's) process consists in igniting a mixture of two parts potash, two parts coke or bituminous coal (steinkohlen) and one part iron turnings in an open vessel

permitting the access of air." Erdmann and Marchand in the "*Journal für Praktische Chemie*" vol. 26, page 413.

This formula has since been varied only by increasing the proportion of powdered iron.

Where an iron tube is used as a catalytic agent as in Siepermann's process English Patents 13,697 of 1889, 9350 and 9351 of 1900 the mixture is in the proportion of one part of sodium carbonate to two parts of charcoal.

In the manufacture of cyanamids and also of cyanids where the reaction takes place with the alkali compound in a plastic condition, that is below the fusion point of the material, an absorption method is used for 60 fixing the nitrogen in the mass of material which is placed in a large retort and the nitrogen is introduced therein under slight pressure. The methods are described as follows:

In the manufacture of cyanamid: "The calcium carbid is reduced to the consistency of flour" and thereafter "the process deviates into two distinct lines of treatment." "At Odda (Norway) the crushed carbid is 65 placed in cylindrical vertical retorts * * * holding 300-500 kilos." "The absorption of nitrogen proceeds for thirty to forty hours, and is known to be complete by reading the controlling meter." *Nitrogen Compounds and Explosives*, Geoffrey Martin and William Barbour, London (1915) pp. 61-63.

"At Westerregeln, Pians d'Orta and other Continental works the process of manufacture is quite different. Here the powdered carbid is placed in horizontal retorts similar to the retorts used in making coal gas: these are heated externally to 800°-1000° C. by being placed in a gas fired furnace while a stream of nitrogen is forced into the retorts 90 for absorption by the carbid" *Idem* p. 63.

In Bucher's process U. S. Patent 1,120,682 he uses the absorption method, employing a briquetted material, the preparation of which he describes at length assigning the following reasons for abandoning the use of powdered material: page 3, line 35 and following "It is hence more advantageous to use the charge in briquetted form to avoid the disadvantages inherent in the use of powders since with the latter there is a liability

to the clogging of the small openings which admit the nitrogen, with the consequent disturbance of the process: while further a sintered charge in the retort may be somewhat difficult to remove."

"Upon trial of powdered charges of the above description, in continuously acting furnaces of the type hereinafter described, the difficulties were found to be much greater than were subsequently encountered when briqueted charges were used: while further with the powder, under mechanical force, including the action of gravity, the heated charge became compact or gradually briqueted so that after cooling it was very difficult to remove it with an iron chisel and hammer." The advantage of the use of powdered material over a briqueted mass or bulk such as he employs is stated by Bucher (p. 2 line 92) as follows: "In the first of my copending applications, it is shown that the cyanid formation takes place very rapidly when the charge used is in form of powder" * * * thus showing that proximity of the particles of carbon to those of iron is not an essential to rapid or complete reaction between the active materials.

In all of these absorption methods for fixing the free nitrogen or ammonia gas in combination, the capacity of the furnace is limited by the time required for the nitrogen gas to permeate the mixture.

At the Westerregelm and other Continental works above cited, the "overheating of the walls ensues, and the cyanamid, on cooling, sets to a rocklike mass on the walls of the retorts and has to be forcibly knocked out. Hence the retorts are subjected to a severe wear and tear." *Industrial Nitrogen Compounds and Explosives*, page 63.

From this review of the state of the art it is evident that the use of powdered materials in the proportions of two parts of carbon to one of the alkali compound and of iron in requisite quantity to exert a catalytic effect in lowering temperature, is not novel; up to the present time however the absorption of nitrogen into a bulk of material with its attendant disadvantage of enormous consumption of time for the completion of the process has been and is necessary where the reaction is effected with the materials unfused.

And no practical way of removing the product from the retort when a powdered material is fed therein has been discovered.

I will now illustrate my process as applied to the production of sodium cyanid. In this case the mixture will preferably comprise one part of soda ash or sodium carbonate (Na_2CO_3), three parts of powdered iron and three parts of a carbonaceous substance, such as charcoal or coke, which materials are first reduced to a fine powder

and then thoroughly mixed. The soda ash will be found to have coated the particles of iron and carbon, thus presenting an extended surface for contact with the nitrogen gas when they are raised to a suitable temperature for combination, while maintained in a diffused mass.

In order to secure contact of the nitrogen with the active materials under these conditions I prefer to utilize an elongated section of iron pipe, or tube, which is positioned vertically and preferably has a height of 50 feet or thereabout and a diameter or cross-section so limited that the heated material while descending by gravity from the upper part of the tube will substantially all of it engage with and adhere to the inner wall of the tube. When it is desired to increase the tonnage capacity of the tube the cross-section or diameter may be increased and the tube mounted to be variably positioned at a very slight angle in any direction from the vertical center. I deliver a supply of the powdered mixture into such tube at or near its upper end so that it will descend, by gravity, in a diffused mass until it contacts with the inner wall of the tube and adheres thereto. I also deliver a supply of nitrogen, into the tube, at or near its lower end: the nitrogen being preferably preheated to the temperature of combination for the carbon and the sodium content of the sodium carbonate therewith, and I regulate the temperature of the nitrogen supply so that when the heat of combination, generated by the chemical reactions occurring in the heat zone of the tube, is released, the temperature therein shall not be substantially increased thereby. In practice I prefer to maintain a temperature of about 1000° to 1100° C., though the temperature may be varied and yet produce the cyanid in commercial quantities, I also supply heat externally to the furnace as necessary to maintain the required temperature.

As when heated, the sodium carbonate and cyanid product becomes plastic and viscid, I take advantage of their adhesive quality to cause the heated particles of the mixture to contact with the inner wall of the tube in the course of their descent and adhere thereto, as heretofore explained thus accumulating and forming an inner skin or coating thereon. Owing to the enormously extended surface of the active materials exposed for contact, with the nitrogen, when pulverulent materials are used, the reaction is effected as to substantially all of the material before the particles become fixed by adhesion to the wall and is completed as to all thereof in an inconsiderable period thereafter. When it is desired to remove treated material from the wall and chamber I preferably assure the effective treatment of all of the adhering

surface particles by sealing the chamber and introducing nitrogen under slight pressure for a few minutes.

At convenient intervals I slice down the accumulations of material adhering to the inner wall with a reamer having a cutting edge which operatively descends from the upper end of the tube for that purpose and is then returned to its normal position, and 10 remove the heated material while in a plastic condition through a suitable valve at the bottom of the tube thus rendering the commercial treatment of powdered material effective and practical by a continuous process, which is not substantially interrupted by these steps for the detachment and removal of material.

I am filing on the same date herewith an application for U. S. Letters Patent for an 20 apparatus for producing cyanogen compounds wherein I show a practical method for the removal of the plastic material from the inner face of the chamber wall and for its removal from the chamber while in a 25 plastic condition, but do not confine myself to the method there shown as any suitable structure may be used and any suitable mechanical device for handling the plastic material and for its removal from the chamber 30 without substantial interruption of the continuity of the process. Upon removal from the retort the treated material is given such further treatment in any usual manner as required to separate the cyanid content from 35 the other material.

In the practice of my process I retain the material within the heated zone of the chamber until the treatment is complete and the material ready for removal from the chamber, and I utilize the inner wall of the chamber within the heated zone for the accumulation 40 of the treated material and its retention until convenient to remove it, thus insuring a high conversion of the material.

As is apparent to one skilled in the art the process is equally adapted for the production 45 of a cyanamid, the catalytic agent and carbon being omitted and a finely comminuted carbide of the alkali metal being employed. In such case, if necessary temperature conditions are observed, the reaction will substantially occur while the material is diffused in the body of the reducing chamber or adhering to the wall thereof, and the time 50 required for completing the operation will be reduced to an inconsiderable period. The material is removed from the wall and withdrawn from the tube at appropriate intervals while in a plastic condition, as heretofore described: Crude cyanamid of the same metal may be added as a catalyzing agent.

I do not confine myself to the use of iron as a catalytic agent as it is well known that several other elements and substances may

be used in the place thereof but I find iron is the most economical for use on a commercial scale.

I preferably use decarburized iron, as it is known that the reaction involved in the producing of a cyanid of an alkali metal in the presence of carburized iron results in its decarburization and likewise that when decarburized iron is used the iron undergoes no perceptible change and may be used repeatedly.

My process may be varied by the use of briquets such as described in the Bucher process heretofore referred to and, as thus applied, the pulverulent materials mixed in the desired proportions are first briqueted and then continuously delivered to the heated zone and permitted to descend by gravity therein, but, before such descent is completed, they are caused to adhere to the inner wall of the reducing chamber, a continuous supply of nitrogen is delivered into the chamber and a reducing temperature maintained therein. As the time element is extended by the necessity for the absorption of the nitrogen by the briquets, the coating on the wall of the chamber is removed from the wall and the furnace, at more extended intervals, but is so removed while in a plastic condition, thus obviating the difficulties encountered in the practice of his process.

Having thus specified, shown and described the same, I claim as novel and my invention:

1. A process for the production of a cyanogen compound from an initially combined alkali metal, initially free nitrogen and carbon, or a carbonaceous material, in the presence of a catalytic agent, which includes the pulverizing and mixing of the solid materials in such proportions as to supply sufficient carbon for combination with the alkali metal present when brought into the presence of free nitrogen and sufficient quantity of a suitable catalytic agent to effectively reduce the temperature for combination of the active participants in the reaction to form a cyanogen compound and in effecting such reaction by bringing a continuous supply of the mixed material while in a diffused mass into the presence of free nitrogen in a zone heated to the temperature of combination for the active elements and in causing such diffused mass during its descent in the reducing chamber limiting such zone and in the presence of such nitrogen supply to adhere to the inner wall of such chamber and in removing the adhesive mass from the wall and the chamber, at appropriate intervals, while yet in a plastic condition, substantially as described.

2. A process for the production of a cyanogen compound from an initially combined alkali metal, nitrogen admixed with

other gases and carbon, or a carbonaceous material, in the presence of a catalytic agent, which includes the pulverizing and mixing of the solid materials in such proportions as to supply sufficient carbon for combination with the alkali metal present when brought into the presence of such nitrogen and sufficient quantity of a suitable catalytic agent to effectively reduce the temperature for combination of the active participants in the reaction to form a cyanogen compound and in effecting such reaction by bringing a continuous supply of the mixed material while in a diffused mass into the presence of such nitrogen in a zone heated to the temperature of combination for the active elements and in causing such diffused mass during its descent in the reducing chamber limiting such zone and in the presence of such nitrogen supply to adhere to the inner wall of such chamber and in removing the adhesive mass from the wall and the chamber, at appropriate intervals, while yet in a plastic condition, after sealing such chamber and

supplying nitrogen thereto under pressure for a short time, substantially as described.

3. The process of producing carbon-nitrogen-metal compounds which comprises showering into a reaction space an intimate mixture comprising an alkali metal compound and carbonaceous matter, maintaining in said reaction space an atmosphere consisting largely of nitrogen, heating said reaction space to a temperature sufficient to promote a nitrogen fixing reaction among the materials, causing the product of said reaction to adhere to the walls bounding the reaction space and removing the accumulations of reaction product from the walls at intervals.

Signed at New York, in the county of New York and State of New York, this seventh day of December, A. D. 1916.

JOHN DIX MORGAN.
